United States Patent Office.

ALONZO HEBBARD, OF NEW YORK, N. Y.

Design No. 3,616, dated August 17, 1869.

DESIGN FOR HANDLE OF SPOONS.

The Schedule referred to in these Letters Patent and making part of the same.

To all whom it may concern:

Be it known that I, ALONZO HEBBARD, of the city, county, and State of New York, have invented or produced a new and original Design for the Handles of Spoons and Forks, and other articles of table-cutlery; and I do hereby declare that the following is a full description of the same, reference being had to the accompanying drawings, forming a part of this specification.

Figure 1 is a representation of the handle of the spoon, without the bowl or blade attached thereto.

Letter *a* represents the lower half of the stem or handle of the spoon, of a sexagonal form, and having on it, at its shank or point of junction with the bowl, a thin button-shaped collar, *b*, with a bead-like edge, and supported or strengthened at each side of the button by collars *c*, with smooth edges, and of less diameter than the collar *b*.

At the upper end of the stem *a* is also attached a button with a bead-like edge, and supported by smaller collars, as just described, as forming the base, upon which is constructed the part commonly called the shield of the handle of a spoon. This part is composed

of a central cylindrical stem, *d*, having on it, at midway of its length, an oval-shaped ferrule, *e*, and terminating at the top in a drop-like head, *f*, and surrounded by a small globular-formed button, *g*.

At each side of the central stem *d* is arranged a figure, *h*, representing an Egyptian lotus, the stem *i* of which unites with the central stem *d*, at its junction with the button forming the head or upper end of the stem *a*, and the inner point *k*, of the lotus-leaf or flower, is attached to the sides of the drop *f*, and thus secures the flower to the handle to complete the design.

Having now described my new design for the handles of spoons, forks, and other articles of table-cutlery, I will proceed to set forth what I claim, and desire to secure by Letters Patent of the United States.

I claim the new and ornamental design for the handles of spoons, forks, and other articles of table-cutlery, as hereinbefore described.

ALONZO HEBBARD.
